[57] **ABSTRACT**

A device for generating a random pulse sequence provides the randomness of the occurrence of each pulse level in the pulse sequence. In general, it is known that the randomness of the binary pulse train is achieved by logical circuits operating on the Galois field GF(2). However, how to generate a random multi-level pulse train was not known heretofore. The multi-level pulse generator presented here comprises unit delay elements such as flip-flops arranged in a plurality of lines and rows and logical circuits to perform logical operations on the outputs from the unit delay elements on the Galois extension field GF(p^k). (p is a prime number)

The randomness of this output is mathematically assured.

DEVICE TO GENERATE PSEUDO-RANDOM MULTI-LEVEL PULSE SEQUENCE

BACKGROUND OF THE INVENTION

This invention relates to a device to generate a random pulse sequence, and particularly a random pulse sequence of multi-level.

Heretofore, a random multi-level pulse sequence generator comprised a binary random pulse sequence generator, a serial-parallel converter and a multi-level converter.

The pseudo-random binary pulse train from the generator is converted into a plurality of binary parallel pulse trains in the series-parallel converter. The number of these plural binary parallel pulses corresponds to the number of levels to be converted. Thereafter, the parallel pulse trains are combined with each other in accordance with the logical rule in the multi-level converter. The logical rule used here is predetermined according to the various combinations of patterns in binary pulse trains at each time instance.

However, the randomness of the multi-level pulse sequence thus obtained has not been satisfactory as will be hereinafter described, and furthermore it is not as assured mathematically.

SUMMARY OF THE INVENTION

An object of this invention is to provide a device to generate a multi-level pulse sequence which is substantially random in the occurrence of each level, furthermore, this randomness is mathematically assured.

According to this invention a pseudo-random multi-level pulse sequence generator is provided which comprises, m columns of unit delay means for storing m output state vector X_i where $i = 1, 2 \dots m$, which are elements of a Galois field, means for individually multiplying the output state vector X_m from the last column of unit delay means by each h_i , where $i = 0, 1, 2 \dots m-1$ and where each h_i is an element of the same Galois extension field and multiplication is over the Galois extension field, means for adding over the Galois extension field Y_i and X_i for $i = 1, 2 \dots m-1$, where Y_i is the product of X_m and h_i , and periodically shifting the resultant sum to the column $i+1$ delay unit means, the resultant sum being the new X_{i+1} , means for periodically shifting Y_o , which is the product of X_m and h_o into the first ($i=1$) column of unit delay means to form the new state vector X_1 , and means for converting the element Y_o into a multi-level pulse, wherein said multiplying means may be a direct input output connection for $h_i = 1$ and the absence of any connection for $h_i = 0$.

BRIEF DESCRIPTION OF THE DRAWINGS

FIG. 1 is a block diagram showing a conventional device to generate pseudo-random multi-level pulse sequences.

FIG. 2 is a block diagram showing an example of device to generate a pseudo-random multi-level pulse sequence according to the present invention.

FIGS. 3 and 4 are block diagrams showing multipliers for the multiplication on the Galois extension field $GF(2^2)$ by $(1, 0) = \alpha$ and $(1, 1) = \alpha^2$, respectively.

FIGS. 5 and 6 are both block diagrams showing the pseudo-random 4-level pulse sequence generators according to the present invention.

FIGS. 7, 8, 9, 10, 11, and 12 are block diagrams showing multipliers for the multiplication on the Galois

extension field $GF(2^3)$ by $(0, 1, 0) = \alpha$, $(1, 0, 0) = \alpha^2$, $(0, 1, 1) = \alpha^3$, $(1, 1, 0) = \alpha^4$, $(1, 1, 1) = \alpha^5$, and $(1, 0, 1) = \alpha^6$, respectively.

FIGS. 13 and 14 are both block diagrams showing, pseudo-random 8-level pulse sequence generators according to the present invention.

FIG. 15 is a block diagram showing the pseudo-random 9-level pulse sequence generator according to the present invention.

FIG. 16 is a block diagram showing a multiplier for the multiplication over the Galois extension field $GF(3^2)$ by $(1, 0) = \alpha$.

FIG. 17 is a block diagram showing a conventional pseudo-random 8-level pulse generator.

FIG. 18 is a block diagram showing the pseudo-random 8-level pulse generator according to the present invention.

FIG. 19 is a graphical representation of auto-correlation of output pulse sequences from a pulse generator shown in FIG. 17.

FIG. 20 is a graphical representation of auto-correlation of output pulse sequences from a pulse generator shown in FIG. 18.

DESCRIPTION OF THE PREFERRED EMBODIMENT

FIG. 1 represents the prior art random multi-level pulse sequence generator as described in the above background section. The generator includes the binary random pulse sequence generator 1, the serial-parallel converter 2, and the multi-level converter 3. As mentioned before, the pseudo-random multi-level pulse generator according to this invention is composed in the following manner. Firstly, there are selected a plurality of unit delay elements which can store p -states for storing one of plural states.

The plurality of the unit delay elements are arranged in k -lines and m -columns. In this case, p must be a prime number. Since the number of lines of the unit delay elements is k , the content in each column of the unit delay elements corresponds to an element over the Galois extension field $GF(p^k)$, well known in the modern algebra.

Then logical operations over $GF(p^k)$ are performed on those elements of $GF(p^k)$.

Let these elements of $GF(p^k)$ be denoted as $A_1, A_2, \dots, A_m$ from the first column to the m -th column. Therefore, the element of the m -th column, that is, the final one is represented as A_m . The element A_m is respectively multiplied on $GF(p^k)$ by the parameters $h_0, h_1, \dots, h_{m-1}$, which are also the elements of $GF(p^k)$.

The product of h_0 and A_m is fed back to the first column of the unit delay elements, while the products of h_1 and A_m , h_2 and $A_m, \dots, h_{m-1}$ and A_m are supplied to adders modulo p , wherein the products are summed with the outputs from the first, second, $\dots, m-1$ th columns in the unit delay elements, respectively. And thereafter, the results are supplied to the corresponding subsequent column. Additionally, the product of h_0 and A_m is simultaneously converted into a multi-level pulse sequence.

The selection of the parameters $h_0, h_1, \dots, h_{m-1}$ will hereinafter be clarified.

Referring to FIG. 2 and others, some embodiments of this invention will be described hereinafter.

At first consider the case that the number of levels is a power of 2, such as 2^2 (= 4 levels), 2^3 (= 8 levels), 2^4 (= 16 levels), for simplicity, i.e. the case where $p = 2$.

Each of 2^k levels in pulse trains can be represented by k -dimensional binary vectors which elements correspond to the states 1 and 0 of k binary unit-delay elements arranged in parallel.

As shown in FIG. 2, unit delay elements (5) are arranged in k lines and in m columns (m is positive integer). In other words, that the k -lines of unit delay elements, that is, $S_{11}, S_{21}, \dots, S_{m-11}, S_{m1}, S_{12}, S_{22}, \dots, S_{m-12}, S_{m2}, \dots, S_{1k}, S_{2k}, \dots, S_{m-1k}, S_{mk}$ are provided. The states "1" and "0" of k unit delay elements $S_{i1}, S_{i2}, \dots, S_{ik}$ ($i = 1, 2, \dots, m$) in the i th column may express one of 2^k state vectors. The state vector of k unit delay elements will hereinafter be expressed by

$$X_i = (x_{i1}, x_{i2}, \dots, x_{ik})$$

where $x_i = 1$ or 0, $i = 1, 2, \dots, m$.

There are provided multipliers $7_m, 7_{m-1}, \dots, 7_1$ equal to the number of columns of the arrangement of the unit delay elements (5). The multipliers (5) are not normal multipliers but are multipliers over the Galois extension field $GF(2^k)$ well known in modern algebra.

The multiplying rule over the Galois extension field, for instance, $GF(2^2)$ is shown in Table 1, wherein the $2^2 = 4$ elements, that is $(0, 0) = 0, (0, 1) = 1, (1, 0) = \alpha$ and $(1, 1) = \alpha^2$ of the Galois extension field $GF(2^2)$ are indicated by a, b, c and d , respectively. In the table the product of any two elements is found by locating the intersection of a vertical line extending from one element in the upper row and a horizontal line extending from the other element in the left most column.

TABLE 1

x	a	b	c	d
a	a	a	a	a
b	a	b	c	d
c	a	c	d	b
d	a	d	b	c

These multipliers 7_i multiply the outputs of the corresponding stage of the shift registers by the constant h_i .

The constant h_i is an element on the Galois extension field $GF(2^k)$. For example, in case of $GF(2^2)$, this is expressed by one of $(0, 0) = 0, (0, 1) = 1, (1, 0) = \alpha$, and $(1, 1) = \alpha^2$. Generally speaking, the multiplication on $GF(p^k)$ (p is a prime number) can be performed using multipliers and adders mod p . This is explained later by an example. For the detailed description, refer to the document (1) "Algebraic Coding Theory" authored by E.R. Berlekamp, pp. 44-46.

Next, consider how to determine the constant parameter h_i ($i = 0, 1, 2, \dots, m-1$) of $GF(2^k)$ in detail. Consider polynomial $h(x) = x^m - h_{m-1}x^{m-1} - h_{m-2}x^{m-2} - \dots - h_1x - h_0$.

This polynomial is hereinafter called a "tap polynomial."

The addition and multiplication in the expression of the tap polynomial are performed on $GF(2^k)$.

In the polynomial, the constant h_i 's ($i = 1, 2, \dots, m-1$) are selected so that the polynomial satisfies the following conditions:

1. There exists no such a polynomial with coefficients from $GF(2^k)$, of a degree more than one that divides $h(x)$.
2. $h(x)$ divides $x^n - 1$ if $n = (2^k)^m - 1$, but does not divide $x^n - 1$ if $n < (2^k)^m - 1$.

The division here is, of course, performed on $GF(2^k)$. The polynomial $h(x)$ satisfying these conditions can be easily searched by a computer. Eventhough, the number of such a polynomial will increase enormously as the degree m increases, some examples of such a tap polynomial will be tabulated.

1 In case of $GF(2^2)$; 4 levels

The elements of $GF(2^2)$ can be represented as $(0, 0) = 0, (0, 1) = 1, (1, 0) = \alpha$, and $(1, 1) = \alpha^2$, respectively, in accordance with the reference (1) mentioned before.

degree Example of the Tap polynomial $h(x)$

2	$x^2 - x - \alpha$, $x^2 - x - \alpha^2$, $x^2 - \alpha x - \alpha$
3	$x^3 - x^2 - x - \alpha$, $x^3 - x^2 - \alpha x - \alpha^2$, $x^3 - x^2 - \alpha^2 x - \alpha$
4	$x^4 - x^2 - \alpha x - \alpha^2$, $x^4 - \alpha x^2 - \alpha x - \alpha$
5	$x^5 - x - \alpha$, $x^5 - \alpha x - \alpha$, $x^5 - \alpha^2 x^2 - \alpha x - \alpha^2$
6	$x^6 - x^2 - x - \alpha$, $x^6 - \alpha x^2 - \alpha^2 x - \alpha$
7	$x^7 - x^2 - \alpha x - \alpha^2$, $x^7 - x^2 - \alpha^2 x - \alpha$
8	$x^8 - x^3 - x - \alpha$, $x^8 - x^3 - x - \alpha^2$
9	$x^9 - x^2 - x - \alpha$, $x^9 - x^2 - x - \alpha^2$
10	$x^{10} - x^3 - \alpha x^2 - \alpha^2$

2. In case of $GF(2^3)$; 8 levels

Similarly, the elements of $GF(2^3)$ can be represented as $(0, 0, 1) = 1, (0, 1, 0) = \alpha, (1, 0, 0) = \alpha^2, (0, 1, 1) = \alpha^3, (1, 1, 0) = \alpha^4, (1, 1, 1) = \alpha^5$, and $(1, 0, 0) = \alpha^6$, respectively.

degree Example of the Tap polynomial $h(x)$

2	$x^2 - x - \alpha^3$, $x^2 - x - \alpha^6$
3	$x^3 - x - \alpha$, $x^3 - x - \alpha^4$
4	$x^4 - x - \alpha^3$, $x^4 - x - \alpha^5$
5	$x^5 - x^2 - x - \alpha^6$
6	$x^6 - x - \alpha^2$

3. In case of $GF(2^4)$; 16 levels

The elements of $GF(2^4)$ can be represented as $(0, 0, 0, 0) = 0, (0, 0, 0, 1) = 1, (0, 0, 1, 0) = \alpha$, $(0, 1, 0, 0) = \alpha^2, (1, 0, 0, 0) = \alpha^3, (0, 0, 1, 1) = \alpha^4$, $(0, 1, 1, 0) = \alpha^5, (1, 1, 0, 0) = \alpha^6, (1, 0, 1, 1) = \alpha^7$, $(0, 1, 0, 1) = \alpha^8, (1, 0, 1, 0) = \alpha^9, (0, 1, 1, 1) = \alpha^{10}$, $(1, 1, 1, 0) = \alpha^{11}, (1, 1, 1, 1) = \alpha^{12}, (1, 1, 0, 1) = \alpha^{13}$, $(1, 0, 0, 1) = \alpha^{14}$.

degree Example of the Tap polynomial $h(x)$

2	$x^2 - x - \alpha^7$, $x^2 - x - \alpha^{11}$
3	$x^3 - x - \alpha^7$, $x^3 - x - \alpha^{14}$
4	$x^4 - x^2 - \alpha x - \alpha^2$, $x^4 - x^2 - \alpha x - \alpha^7$
5	$x^5 - \alpha x - \alpha^2$

Returning to FIG. 2, assuming that the outputs of the multipliers 7_m are represented as the state vector $Y_m = (y_{m1}, y_{m2}, \dots, y_{mk})$, the elements are supplied to the initial column consisting of the unit delay elements $S_{11}, S_{12}, \dots, S_{1k}$ while the outputs of the other multipliers $7_{m-1}, \dots, 7_1$ and the outputs of the respective delay elements of first, $\dots, (m-1)$ th columns are summed on the Galois extension field $GF(2^k)$, and thereafter the outputs of adders supplied to the respective delay elements of the second, $\dots, m$ th columns. The addition on the Galois extension field $GF(2^k)$ may be performed by exclusive OR wherein elements of one state vector are summed to the corresponding elements of the other state vector.

Therefore, the elements $y_{m-11}, y_{m-12}, \dots, y_{m-1k}$ of the output Y_{m-1} of the multiplying circuit 7_{m-1} are respectively supplied to the exclusive OR circuits (called an adders, hereinafter) $S_{11}, S_{12}, \dots, S_{1k}$, and the outputs of the delay elements $S_{11}, S_{12}, \dots, S_{1k}$ are supplied to the adders $S_{11}, S_{12}, \dots, S_{1k}$, and the outputs of the exclusive OR of these two inputs are supplied to the subsequent row of the unit delay elements $S_{21}, S_{22}, \dots, S_{2k}$. Like-

wise, the exclusive OR operations between the outputs of the multipliers $7_{m-2}, \dots, 7_2$ and the outputs of the corresponding unit delay element row are also carried out, and the outputs are simultaneously supplied to the next row of unit delay elements, respectively. Similarly, the elements $y_{11}, y_{12}, \dots, y_{1k}$ of the output vectors of the multiplier 7_1 and the outputs of the unit delay elements $5_{m-11}, 5_{m-12}, \dots, 5_{m-1k}$ of $(m-1)$ th row are exclusively added by the adder $8_{m-11}, 8_{m-12}, \dots, 8_{m-1k}$, and these outputs are shifted to the unit delay elements $5_{m1}, 5_{m2}, \dots, 5_{mk}$ of the final rows, respectively.

The elements $y_{m1}, y_{m2}, \dots, y_{mk}$ of the outputs Y_m of the multiplier 7_m are respectively supplied through the lines $11_1, 11_2, \dots, 11_k$ to the multi-level pulse converter (10). The converter (10) feeds out a pulse of level corresponding to the input state vector at the respective clocks, and is functionally similar to the D-A converter (3) shown in FIG. 1.

Then, the operation of the pseudo random multi-level pulse sequence generator will now be described. At first, the respective unit delay elements (5) are set to any state other than a state such that all unit delay elements take the "0" state. The state vector of m th column, $X_m = (x_{m1}, x_{m2}, \dots, x_{mk})$ is supplied to the multiplier 7_i ($i = 1, 2, \dots, m$) at the next clock pulse and the multiplication of the x_m and h_{m-i} ($i = 1, 2, \dots, m$) are performed on the Galois extension field $GF(2^k)$. The results $y_i = (y_{i1}, y_{i2}, \dots, y_{ik})$ of the multiplication are obtained therein, and the outputs of the unit delay elements 5_{ij} and $Y_{(m-i)j}$ ($i = 1, 2, \dots, m-1; j = 1, 2, \dots, k$) are exclusively added by the adders 8_{ij} within the same clock, and the results are shifted to the subsequent unit delay elements 5_{i+1j} ($j = 1, 2, \dots, k$) to be stored. And, the outputs y_{mj} ($j = 1, 2, \dots, k$) of the multiplying circuit 7_m are shifted to the delay elements 5_{1j} ($j = 1, 2, \dots, k$) so as to be stored. The aforementioned operations are all operated within the same clock time. Then, the pulses are supplied through k parallel lines $11_1, 11_2, \dots, 11_k$ to the converter (10), corresponding to the values "1" and "0" of the outputs $y_{m1}, y_{m2}, \dots, y_{mk}$. In the next clock, the same operation will be repeated.

Thus, considering the series of parallel pulse trains fed out, the repetition period is verified to be 2^{km-1} in the same way as for a binary pseudo-random sequence. Thus the randomness becomes more distinguished as the increase in the number m of rows in all unit delay elements. Therefore, the larger the number m is made to be, the smaller the auto-correlation of the sequence of the parallel pulse trains will be, and consequently it is mathematically proven to be random.

Next consider the actual realization of a pseudo-random multi-level pulse generator based on several tap polynomials tabulated before.

At first, in case of $4 (= 2^2)$, it is apparent that each of the $2^2 = 4$ state vectors corresponds respectively to the element $(0, 0), (0, 1), (1, 0)$ and $(1, 1)$ of the Galois extension field $GF(2^2)$. According to the above described reference (1), the circuit for multiplying (x_2, x_1) by α or $(1, 0)$ over the Galois extension field $GF(2^2)$ is shown in FIG. 3. It follows that the contents x_1 and x_2 stored in the unit delay elements 12_1 and 12_2 are summed in the adder 13 in the manner of exclusive OR, and the outputs are supplied to the unit delay element 14_2 , and the content of the element 12_2 is supplied to the unit delay element 14_1 . The contents y_1 and y_2 of

the elements 14_1 and 14_2 represent the product of (x_2, x_1) and α .

For example, assuming that (x_2, x_1) is $(1, 0)$, the product of this and $\alpha = (1, 0)$ becomes "1" because $x_2 = 1$ is presented as y_1 as it is and y_2 is the exclusive OR of $x_1 = 0$ and $x_2 = 1$, and resulting $(y_2, y_1) = (1, 1)$. Assuming that $a = 0, b = 1, c = \alpha, d = \alpha^2$, then the product of $(x_2, x_1) = (0, 1) = b$ and $\alpha = (1, 0) = c$ is represented by $d = (1, 1) = \alpha^2$ from the Table 1, and it is understood that the circuit shown in FIG. 3 operates the multiplication between (x_2, x_1) and α over the Galois extension field $GF(2^2)$. Similarly, the circuit for multiplying (x_2, x_1) by α^2 or $(1, 1)$ over the Galois extension field $GF(2^2)$ is as shown in FIG. 4, wherein the part corresponding to that in FIG. 3 is designed by the same reference numerals. If (x_2, x_1) is multiplied by $(0, 1) = 1$, the product (y_2, y_1) is the same as (x_2, x_1) , and if (x_2, x_1) is multiplied by $(0, 0)$, the product (y_2, y_1) becomes $(0, 0)$.

FIG. 5 is one realization of the pseudo-random, 4-level pulse sequence generator wherein the tap polynomial $x^3 - x^2 - \alpha^2 x - \alpha$ is selected from the table of the Tap Polynomials of degree 3 for four elements shown hereinbefore. Since the tap polynomial $h(x) = x^3 - x^2 - \alpha^2 x - \alpha$ is degree 3, two lines of unit delay elements (5) have three rows of the unit delay elements $5_{11}, 5_{21}, 5_{31}; 5_{21}, 5_{22}, 5_{32}$. Since the coefficient of x^2 of the tap polynomial is -1 , the constant h_2 of the multiplier 7_1 becomes $(0, 1) = 1$ so that the outputs of the delay elements 5_{31} and 5_{32} are supplied to the adder 8_{21} and 8_{22} as they are. The coefficient of the term of the first degree of the tap polynomial is $-\alpha^2$, the outputs of the delay elements 5_{31} and 5_{32} are multiplied α^2 times in the multiplier 7_2 so as to be supplied to the adders 8_{11} and 8_{12} . The multiplication of α^2 is performed by the circuit shown in FIG. 4. Further, since the coefficient of x^0 is $-\alpha$, the multiplier 7_2 multiplies the outputs of the delay elements 5_{31} and 5_{32} by α , and is constituted by the circuit shown in FIG. 3.

When $x^5 - \alpha^2 x^2 - \alpha x - \alpha^2$ is used as the tap polynomial $h(x)$, the coefficients of x^4 and x^3 are 0. According to the logical rule hereinbefore, when a state vector $X (x_2, x_1)$ is multiplied by 0, the result is represented by $X = (0, 0)$, and even if $(0, 0)$ is added to the other $X (x_2, x_1)$, it is (x_2, x_1) as it is, and therefore the multipliers 7_1 and 7_2 and adders $8_{31}, 8_{32}, 8_{41}$ and 8_{42} are cancelled as shown in FIG. 6. Since the coefficients of x^2 , x and x^0 in the polynomial $h(x)$ are $-\alpha^2, -\alpha$ and $-\alpha^2$ respectively, the multipliers 7_3 and 7_5 may be composed as shown in FIG. 4 and the multiplier 7_4 is composed as shown in FIG. 3.

In the case of the Galois extension field $GF(2^3)$, that is, in the case of the pseudo-random 8-level pulse sequence generator, each of the $2^3 = 8$ state vectors corresponds to each element of the Galois extension field $GF(2^3)$. According to the reference (1) as aforesaid, the circuits for multiplying (x_3, x_2, x_1) by α or $(0, 1, 0)$, $\alpha^2 = (1, 0, 0)$, $\alpha^3 = (0, 1, 1)$, $\alpha^4 = (1, 1, 0)$, $\alpha^5 = (1, 1, 1)$, $\alpha^6 = (1, 0, 1)$ on the Galois extension field $GF(2^3)$ can be composed as shown in FIGS. 7 to 12. Referring to these drawings, the state vectors (x_3, x_2, x_1) are stored in the unit delay elements $12_3, 12_2$ and 12_1 , and the state vectors (y_3, y_2, y_1) representing the multiplied results are stored in the unit delay elements $14_3, 14_2$ and 14_1 . (13) designates an adder. Furthermore, the product between (x_3, x_2, x_1) and $(0, 0, 1)$ is equal to the state vector (x_3, x_2, x_1) as it is, while the product be-

tween the (x_3, x_2, x_1) and $(0, 0, 0)$ becomes $(0, 0, 0)$.

The examples of the pseudo random 8-level pulse series generator derived from such facts are shown in FIGS. 13 and 14. In FIG. 13, the multiplier 7_1 and adder S_{21} , S_{22} , S_{23} are omitted, the multiplier 7_2 multiplies by 1, and the multiplier 7_3 is as shown in FIG. 10 in circuit to multiply by α^4 . In FIG. 14, the multiplier 7_6 multiplies by α^2 consisting of the circuits shown in FIG. 8.

Likewise, the device to generate the pseudo-random multi-level pulse sequences of $16 (= 2^4)$ or more levels which is generally indicated at 2^k can be realized.

Eventhough all the realizations described so far are concerned with the number of multi-levels as a power k of 2, the present invention may also be applied to the cases where the number of levels is a power of p , which is a prime number other than 2. In such applications, the states which can be taken by each of the unit-delay elements shown in FIG. 2 are not limited to the above described "0" and "1" but generally p states can be taken in each unit delay element. Such an element can be realized, for example, by the parallel combination of unit delay elements (such as flip-flop registers) for bi-

X_1	X_2	Y_1	Y_2	Z_1	Z_2	$\bar{X}_1$	$\bar{X}_2$	$\bar{Y}_1$	$\bar{Y}_2$	$\bar{Z}_1$	$\bar{Z}_2$	$\bar{X}_1$	$\bar{X}_2$	$\bar{Y}_1$	$\bar{Y}_2$	$\bar{Z}_1$	$\bar{Z}_2$
0	0	0	0	0	0	0	1	0	0	0	0	1	0	0	0	0	0
0	0	0	1	0	0	0	1	0	1	0	0	0	0	1	1	1	0
0	0	1	0	0	0	0	1	1	0	1	0	1	0	1	0	0	1

nary pulses. This will be clarified hereinafter. Furthermore, as in the above described cases for $p = 2, p^k$ ($p \neq 2$) states may also be expressed by parallel disposed k lines of elements, each may take p values. Also, modulo p addition rather than modulo 2 addition is used, the parameters h_i ($i = 0, 1, 2, \dots, m-1$) are replaced by the parameters belonging to the Galois extension field $GF(p^k)$, and the multiplier circuit multiplier over the Galois extension field $GF(p^k)$ rather than $GF(2^k)$. The result is a device which generates a pulse sequence of p^k ($p \neq 2$) levels in the same manner as in the above described realizations.

In this case, the constant parameters h_i ($i = 0, 1, 2, \dots, m-1$) are so selected that the Tap Polynomial $h(x)$ satisfies following conditions:

1. There exists no such a polynomial with coefficients from $GF(p^k)$, degree more than one that divides $h(x)$.
  2. $h(x)$ divides $x^n - 1$ if $n = (p^k)^m - 1$, but does not divide $x^n - 1$ if $n < (p^k)^m - 1$. The division here is, of course, performed on $GF(p^k)$. The polynomial $h(x)$ satisfying these conditions can be easily searched by a computer.

For practical examples, a case of $p = 3, k = 2$, namely $3^2 = 9$ -levels will be described in detail hereinafter. First, as a Tap Polynomial satisfying the above conditions, a second order polynomial $x^2 - x - \alpha$ is consid-

X ₁	X ₂	Y ₁	Y ₂	Z ₁	Z ₂	X ₁	X ₂	Y ₁	Y ₂	Z ₁	Z ₂	X ₁	X ₂	Y ₁	Y ₂	Z ₁	Z ₂
0	0	0	0	0	0	0	1	0	0	0	1	1	0	0	0	0	1
0	0	0	1	0	1	0	1	0	1	1	0	0	1	0	1	0	0
0	0	1	0	1	0	0	1	1	0	0	0	1	0	1	0	0	0

ered. Herein, in accordance with the reference (1), following expressions are possible.

$$(0, 0) = 0, (0, 1) = 1, (1, 0) = \alpha, (2, 1) = \alpha^2, (2, 2) = \alpha^3, \\ (0, 2) = \alpha^4, (2, 0) = \alpha^5, (1, 2) = \alpha^6, (1, 1) = \alpha^7$$

A pseudo-random 9-level pulse sequence generator with tap polynomial $h(x) = x^2 - x - \alpha$ is indicated in

FIG. 15. Since the Tap polynomial has degree 2, the unit delay elements to store 3 states are arranged in 2 columns, and such an element can be composed of combination of two unit-delay elements such as flip-flop registers each of which can store two states. More specifically, since a pair of unit delay elements can take the four states, $(0, 0)$, $(0, 1)$, $(1, 0)$, $(1, 1)$, one of them, for example, the state $(1, 1)$ is to be inhibited therefrom, and the other three states may be represented by a pair of unit delay elements 16 and 17 in FIG. 15.

Since the coefficient of x in the tap polynomial is -1 the outputs of the elements S_{21} and S_{22} are multiplied by one in the multiplier 7_1 . That is, the outputs of the elements S_{21} and S_{22} are supplied to the adder S_{11} and S_{12} as they are. Since the coefficient of x^0 is $-a$, the outputs of the elements S_{21} and S_{22} are multiplied twice by the multiplier 7_2 . The adders S_{11} and S_{12} are of course adders of modulo 3 respectively.

Assuming that the product modulo 3 of the (x_1, x_2) and (y_1, y_2) is (z_1, z_2) and $0 = (0, 0)$, $1 = (0, 1)$, $2 = (1, 0)$, then the following table can be obtained. However, the state $(1, 1)$ is inhibited therefrom.

It is easy to synthesize a logic circuit by forming a logic formula from the table.

The multiplier for multiplying by α may be composed as shown in FIG. 16 according to the reference (1). Assuming that the state of the elements 16 and 17 in the unit delay element 18₁ is (x_{11}, x_{12}) , the state of the elements 16, 17 in the element 18₂ is (x_{21}, x_{22}) , the state of the elements 16, 17 in the unit delay element 19₁ is (y_{11}, y_{12}) , the state of the elements (16), (17) in the element 19₂ is (y_{21}, y_{22}) , and 9 values of the elements 18₁, 18₂ or 19₁ and 19₂ are expressed by $((x_{11}, x_{12})(x_{21}, x_{22}))$ or $((y_{11}, y_{12})(y_{21}, y_{22}))$. Herein, $x_{i,j}$ and $y_{i,j}$ are equal to "1" or "0" ($i = 1, 2$).

Thus, the value indicated by the state (x_{11}, x_{12}) in the element 18_1 is multiplied by 2 at the multiplier 20 of modulo 3 and the result and the value indicated by the state (x_{21}, x_{22}) in the element 18_2 are summed in the adder 21 of modulo 3, and the result is represented as the state (y_{11}, y_{12}) in the element 19_1 . On the other hand, the state (x_{11}, x_{12}) of the element 18_1 constitutes by itself the state (y_{21}, y_{22}) in the element 19_2 . It should be noted that all of the above operations are performed at every clock time.

Assuming that the sum modulo 3 of the (x_1, x_2) and (y_1, y_2) is (z_1, z_2) and $0 = (0, 0)$, $1 = (0, 1)$, $2 = (1, 0)$, they may be expressed as in the following table. However, the state $(1, 1)$ is inhibited therein.

It is easy to synthesize a logic circuit by forming a logic formula from the table.

As is apparent from the above description, the pseudo random multi-level pulse generator may be composed by simple circuit, and the randomness of the resultant pulse is mathematically assured.

When the auto-correlation of the pseudo random 4-level pulse sequence of the present invention is com-

pared with that of the pseudo random 4-level pulse sequence of the conventional method, it will be found that the auto-correlation of the former is smaller than that of the latter, and therefore, the former has better randomness.

Herein, both the former and the latter generators are assumed to have equal unit delay elements. FIG. 17 is a conventional circuit, wherein a shift register is composed of 7 stages of flip-flop circuits 23, connected in cascade, the input and output of the last stage of the flip-flop circuits 23 being supplied to an adder 24 to perform an exclusive OR operation therein, the output of the adder 24 being feedback to the initial stage of the flip-flop circuits 23, whereby 2-level random pulse generator 1 is constituted.

The 2-level random pulse train from the generator 1 is converted in a parallel converter 2 into three rows of binary pulse trains as previously described with reference to FIG. 1, and three rows of parallel pulse trains are thereafter converted in a D-A converter 3 into a multilevel pulse series having a multilevel such as (000) into -1, (001) into 1, (010) into 3, (011) into -3, (100) into 5, (101) into -5, (110) into 7, and (111) into -7.

The auto-correlation of the output pulse series thus obtained is indicated in FIG. 19.

In FIG. 18, there is indicated a random 8-level pulse sequence generator wherein $p = 2$, $k = 3$, $m = 2$, and the Tap Polynomial $X^2 - X - \alpha^6$ are selected. The auto-correlation of the random 8-level pulse sequence from this device is indicated in FIG. 20.

Comparing the results shown in FIGS. 19 and 20, it will be easily found that the pulse sequences obtained by the pulse sequence generator according to the present invention has far smaller autocorrelation than that of the conventional pulse sequences, whereby the randomness of the former is superior than that of the latter.

I claim:

1. A pseudo-random multi-level pulse sequence generator comprising
  - a. m columns of unit delay means for storing m output state vector X_i where $i = 1, 2 \dots m$, which are elements of a Galois field,
  - b. means for individually multiplying the output state

vector X_m from the last column of unit delay means by each h_i , where $i = 0, 1, 2 \dots m-1$ and where each h_i is an element of the same Galois extension field and multiplication is over the Galois extension field,

- c. means for adding over the Galois extension field Y_i and X_i for $i = 1, 2 \dots m-1$, where Y_i is the product of X_m and h_i , and periodically shifting the resultant sum to the column $i+1$ delay unit means, the resultant sum being the new X_{i+1} ,
  - d. means for periodically shifting Y_0 , which is the product of X_m and h_0 into the first ($i = 1$) column of unit delay means to form the new state vector X_1 , and
  - e. means for converting the element Y_0 into a multi-level pulse, wherein said multiplying means may be a direct input output connection for $h_i = 1$ and the absence of any connection for $h_i = 0$.
2. A pseudo-random multi-level pulse sequence generator as claimed in claim 1 wherein said state vectors X_i , said parameters h_i and products Y_i are elements of a Galois extension field $GF(p^k)$ and wherein each column of unit delay means comprises k individual unit delay means, and p is a prime number.
  3. A pseudo-random multi-level pulse sequence generator as claimed in claim 2 wherein said parameter h_i , $i = 0, 1, \dots, m-1$, satisfy the following conditions for the tap polynomial with one variable x , $h(x) = x^m - h_{m-1}x^{m-1} - h_{m-2}x^{m-2} - \dots - h_1x - h_0$ where additions and multiplications are over the Galois field $GF(p^k)$, said conditions being,
    - a. there exists no such a polynomial with coefficients from $GF(p^k)$, of a degree more than one that divides $h(x)$; and
    - b. $h(x)$ divides $x^n - 1$ if $n = (p^k)^m - 1$, but does not divide $x^n - 1$ if $n < (p^k)^m - 1$.
  4. A pseudo-random multi-level pulse sequence generator as claimed in claim 3 wherein said multi-level pulses are (p^k) - level pulses and wherein each of said individual unit delay means is capable of storing p values.
  5. A pseudo-random multi-level pulse sequence generator as claimed in claim 3 wherein each said unit delay means comprises n flip-flop where $2^{n-1} \leq p \leq 2^n$.
